UNITED STATES PATENT OFFICE.

GUSTAVE HUMBER, OF DENVER, COLORADO.

ARC-LAMP.

1,228,442.

Specification of Letters Patent. Patented June 5, 1917.

Application filed March 29, 1915. Serial No. 17,716.

To all whom it may concern:

Be it known that I, GUSTAVE HUMBER, a citizen of the United States, residing at Denver, county of Denver, and State of Colorado, have invented certain new and useful Improvements in Arc-Lamps, of which the following is a specification.

This invention relates to certain new and useful improvements in arc lamps, and has primarily for its object to provide means whereby a steady light may be maintained without the use of manual interference for feeding the carbons employed therewith as they become burned.

A further object of the invention is to provide means for initially establishing the desired arc between the electrode points and for automatically maintaining the same while the lamp is in operation.

A further and more particular object of the present invention is to provide means for holding the electrodes employed in devices of this character at their points when the lamp is not burning, so as to prevent the same from rubbing together, due to vibrations, and in this connection the invention aims to provide improvements upon the device disclosed in my Patent No. 1,146,498.

The lamp constituting the subject matter of the present application is designed especially to be used upon vehicles, and more particularly upon railway rolling stock, such as locomotives, and inasmuch as lamps of this character now generally in use upon such vehicles are more or less inefficient, due to the fact that they are equipped with such carbon feeding means as to permit of the carbon points chafing each other when the lamp is not in use, the wearing away or rubbing of the carbon points, caused by the vibrations of the vehicle when in motion, is obviated by the employment of the improved carbon or electrode feeding means embodied in the present invention.

With the above mentioned objects in view, together with others which will appear as the description proceeds, the invention resides in the novel combination and arrangement of parts all as will be described more fully hereinafter, and particularly pointed out in the claims.

My invention will be more readily understood by reference to the accompanying drawings, wherein—

Figure 1 is a front elevation of an improved arc lamp embodying my invention,

Fig. 1^a is a fragmentary view illustrating the clutches in the position they assume when the lamp is not in operation.

Fig. 2 is an enlarged fragmentary front elevation of the electrode supporting and feeding mechanism, and,

Figs. 3 and 4 represent respectively a fragmentary front elevation and a longitudinal section of the electrode supporting brackets disclosed in Fig. 2.

Referring now more particularly to the drawings, 10 represents an arc lamp standard or support of conventional form, being provided with the usual foot or base 11 for suitably securing the same in position, and with any preferred form of means 12 for adjusting the standard relative to the base in order that the arc may be properly centered with respect to the reflector with which it may be used.

While the standard or support for the device may be of any preferred shape or construction, the type employed in the present instance I find most convenient for illustrating the application of the device to be hereafter described, and to the upper end of the standard 10 I secure by suitable armed brackets 18 and 19, the carbon or electrode supporting brackets 63 and 64. These brackets are so arranged upon the support as to hold the electrodes 15 in convergent position, with their points substantially meeting adjacent the center of a reflector 16 illustrated diagrammatically in Fig. 1. The brackets 63 and 64 each comprise upper and lower sections 65 and 66 respectively, the upper section 65 being provided at its lower end with a longitudinally extending socket 67 within which a member 68 provided on the upper end of the section 66 is adapted to slide. A coil spring 69 is interposed between the member 68 and the base of the socket 67 to normally force the said sections 66 outwardly. The member 68 is provided with a longitudinally extending groove 70 within which a set screw 71 is adapted to engage to prevent lateral or rotary movement of the member 68, and more particularly to limit the longitudinal movement thereof. The upper sections of the brackets are each rigidly secured to respective brackets 18 and 19. At the lower end of the bracket 13 is arranged an electrode support and guide 23, and inasmuch as the guide on the opposite electrode bracket is identical in construction, a detailed descrip-

70

110

tion of one will be given; it being understood that the description applies equally as well to both. This guide 23 comprises a collar extending outwardly from the front 5 face of the lower end of sections 66 of the electrode bracket and being of substantially the same contour as is the electrode 15 in cross section. The inner walls of the collar are smooth so as to permit of the electrode 10 freely feeding through the same, and in order to permit of a free feed of the electrode the collar is a trifle larger in diameter than is the electrode. An improved electrode supporting clip 25 is provided at the opposite end of each of the brackets 13 and 14, and each clip is adapted to slide longitudinally of its respective electrode bracket, having arms 26 engaging around the longitudinal edges thereof. Upon the outer face of 15 the clip 25 is secured a resilient member or clamp 27. This clamp is secured as at 28 at one end adjacent the outer end of the body of the clip and extends toward the opposite end thereof to engage the upper 20 end of the carbon electrode. In practice the butt end of the electrode is inserted beneath the clamp 27 to be held thereby, and as the carbon is fed longitudinally of the bracket the clip will be free to slide. In this manner 25 a free feed of the electrode is insured and yet the butt end of the electrode is held securely against any lateral movement as the arms 26 snugly engage around the holder member 65.

30 35 Upon the electrode guide or collar at the ends of each of the brackets 63 and 64 is an improved clutch for governing the feeding of the carbons, and each clutch comprises a bar or arm 34 pivoted as at 35 to oscillate 40 in a direction longitudinally of the bracket to which it is attached. The inner end of this bar is provided with a preferably arcuate member 36, provided at its opposite ends with grip members 37 and 38; the same being 45 so arranged that one or the other is in engagement with the electrode carried by the bracket at the extreme opposite positions of the said bar or arm 34, and yet neither will be in contact with the electrodes when the 50 arm 34 is swung to an intermediate position.

55 For operating the clutches above described I provide a pair of rock levers 39 and 40 respectively. These levers are pivoted at their outer ends to brackets 41 depending from the standard 10, and are connected intermediate their ends with the clutches by means of links 42, the latter, in order to permit of adjustment, being made up of 60 separate sections 43 and 44, and threaded together as at 45 at their adjacent ends. To prevent any side movement of the links 42 the section 44 is extended through a sleeve 46 extending outwardly from the 65 bracket adjacent the same. A pin and elong-

gated slot connection 47 permits of rocking movement of the rocker arms 39 and 40 without subjecting the links 42 to strain at the point of connection with the same.

It is my purpose in the present invention 70 to provide a self feeding system for the electrodes, that is, one which when the electric current is admitted to the lamp will establish and maintain an arc at the electrode points of such character as to attain a high 75 degree of efficiency of the lamp, and to this end I provide a solenoid 52 in circuit with the lamp, the same being provided with the usual core 53. A slide bar 54 is provided upon the support 10 and is connected at one end to the adjacent end of the rock levers 39 and 40, and at its opposite end to a rock arm 55, the latter being pivoted intermediate its ends as at 56 upon an ear 57 formed upon the bracket 18. The opposite 80 end of the rock arm 55 is connected to a lever 58, pivoted at 59 upon the standard 10, and connected at one end by a link 60 with the core 53 of the solenoid. A retractile spring 61 is connected to the opposite 85 end of the lever 58 and with the standard 90 95 100 105 110 115 120 125 130 135 140 145 150 155 160 165 170 175 180 185 190 195 200 205 210 215 permitted to gravitate until their ends engage each other and are immediately thereafter engaged by the grip members 36 upon the opposite side of the arm 34 of the clutch 5 to hold the carbons firmly so as to prevent chafing of the ends, that is, to prevent the same rubbing together or chipping when the lamp is not lighted.

When the gap at the points of the carbon 10 becomes so wide as to weaken the current the core of the solenoid will be released as above mentioned and the slide bar 54 will move downwardly, forcing the inner ends of the rock levers 39 and 40 in the same direction. 15 It is to be observed that immediately upon such action the spring 69 within the socket formed in the upper section of the said bracket will force the lower section 66 of the bracket downwardly thereby insuring 20 a perfect and rapid feed of the carbons. Should the movement of the members 66 be insufficient to bring the ends of the electrodes into proper relation, further movement of the levers 39 and 40 and rods 42 25 will swing the clutches 34 so as to remove the jaws 38 from engagement with the electrodes thereby permitting the latter to gravitate into engagement. Upon the meeting of the carbons or electrodes the increased 30 current will cause the solenoid to draw inwardly upon the core thereof, thereby overcoming the pressure of the contractile spring 61 and operating the rock lever 55 to draw upwardly upon the slide bar, thereby rock- 35 ing the clutches upwardly until the clutch faces 38 again engage their respective electrodes, and continued upward movement of the links 42 causes the said electrodes to be pressed inwardly, by reason of pressure by 40 the grip member 38, against the inner surface of the guide, whereupon the said guide which is secured to the member 66, will be moved simultaneously with the said electrode in an upward direction and against 45 the tension of the spring 69. This operation obviously causes the carbon points to be separated, and to remain so until the gap becomes so wide that the current will be weakened, whereupon the above detailed ac- 50 tion will be repeated. It is apparent that by adjustment of the retractile spring 61 the gap between the electrode points can be governed to maintain at all times a proper and efficient arc.

55 To insure the lamp against becoming short circuited, the bracket 19 is insulated as at 72 from the support 10, and the bracket 18 is insulated from the said support as at 72'. The rock levers 39 and 40 are also insulated as at 73 from the slide bar 54.

It is obvious that by the arrangement of the automatic means for feeding the carbons and operating the mechanism connected with the device a proper arc is at all times maintained when the lamp is in operation,

and when the lamp is inoperative the electrode points are held firmly by the clutch elements 36 so as to prevent the same chafing or chipping away through vibrations of the vehicle or body upon which it may be 70 used. It is also apparent that the arrangement of the various parts permits of the device being readily changed from that form illustrated in the preferred form of the device to that disclosed in the modification, 75 without the necessity of additional expense, and without the necessity of skilled help or special tools or instruments.

While in the above described forms I have only illustrated what appears to me to be at 80 the present time the most practicable presentation of the invention, I wish it to be understood that I reserve to myself the right to make various changes and alterations in the form and construction thereof as may 85 fairly fall within the scope of the appended claims.

I claim:

1. In an arc lamp, a pair of brackets arranged in convergent relation, an electrode 90 in each of said brackets extending outwardly therefrom to meet, means for normally forcing said electrodes toward the point of convergence, a pivoted clutch member on each bracket adapted to engage its respective 95 electrode at the limit of movement in each direction, and normally holding said electrode against the action of said forcing means, a solenoid, and a connection between the core of said solenoid and each of said 100 clutch members for operating the latter to release and grip successively each electrode upon continued movement of said core in either outward or inward direction, substan- 105 tially as described.

2. In an arc lamp, a support, a pair of electrode brackets secured to said support in convergent position, each of said brackets comprising a pair of sections slidably connected together at their adjacent ends to permit of extension or retraction thereof, means tending normally to hold said brackets in extended position, an electrode guide adjacent the end of the outermost of each of said sections, a clutch on each guide comprising a pivoted bar provided with means to grip said electrode when moved in either direction upon rocking movement of said pivoted bar, electrodes in said brackets extending through said guides adapted to be 110 gripped by said clutches, and means for operating said clutches, and for simultaneously extending or contracting said brackets, sub- 115 stantially as described.

3. In an arc lamp, a support, an electrode 125 bracket on said support, said bracket comprising a pair of sections slidably connected together at their adjacent ends to permit of extension or contraction of said bracket, means tending normally to hold said bracket 130

in extended position, an electrode guide at the end of one of said sections, an electrode on said bracket extending loosely through said guide, a clutch on said guide provided 5 with means adapted to alternately engage or release said electrode when said clutch is moved in opposite directions, a rock lever, a link extending longitudinally of said bracket and connected at its opposite ends with said 10 rock lever and said clutch, and means for rocking said rock lever, substantially as described.

4. An electrode bracket comprising a pair of sections adapted to slidably engage with 15 each other at their adjacent ends, one of said sections being provided at its end with a longitudinally extending socket, a member on the adjacent end of the other of said

sections for sliding engagement within said socket, a spring interposed between the end 20 of said member and the bottom of said socket normally forcing said member outwardly, said member being provided with a longitudinally extending groove, a set screw on said socket section extending through the 25 same for engagement within said groove, and means on said sections for loosely supporting an electrode, substantially as described.

In testimony whereof I have signed my 30 name to this specification in the presence of two subscribing witnesses.

GUSTAVE HUMBER.
